UNITED STATES PATENT OFFICE.

THEODORE LEONARD KRUPITZER, OF SOUTH JACKSONVILLE, FLORIDA.

BRICK-CLEANING MACHINE.

Application filed April 18, 1925. Serial No. 24,282.

To all whom it may concern:

Be it known that I, THEODORE L. KRUPITZER, a citizen of the United States, and a resident of South Jacksonville, in the county 5 of Duval and State of Florida, have invented certain new and useful Improvements in Brick-Cleaning Machines, of which the following is a specification.

My present invention relates generally to 10 brick cleaning machines, and more particularly to machines for cleaning used brick in preparation for re-use, more especially paving brick, and of that type embodying an open die with cutters, brick guides adjacent 15 to the die, and means engageable with the brick for forcing the same through the die against the action of the cutters, certain of which are adjustable and spring controlled with the object in view of clearing off 20 surface collections such as tar and the like as nearly as possible to the surfaces of the brick itself.

The primary object of my present invention is the provision of a simple, comparatively inexpensive device both as to first cost and upkeep, which will be strong and durable, as well as effective and efficient in use.

In the accompanying drawings which illustrate my present invention and form a 30 part of this specification,

Figure 1 is a top plan view,

Figure 2 is a side elevation,

Figure 3 is a bottom plan view of one of 35 the cutter bars,

Figure 4 is a transverse sectional view therethrough on the line 4—4 of Figure 3,

Figure 5 is a cross section through the apparatus adjacent to the die and showing the 40 latter in front elevation,

Figure 6 is a sectional view taken on the line 6—6 of Figure 5,

Figures 7 and 8 are detail sections taken 45 respectively on the lines 7—7 and 8—8 of Figure 5,

Figure 9 is a cross section through the frame on the line through the plunger and plunger guides, and

Figure 10 is a detail side view of the brick 50 engaging end of the plunger.

Referring now to these figures, and particularly to Figures 1 and 2, my invention proposes the use of an elongated rectangular frame, which may be supported upon wheeled 55 trucks and the like as well as upon a solid foundation or bed, depending upon whether

or not portability is desired, it being understood that in any event the frame is effectively and solidly held in a horizontal position in order that the bricks to be cleaned 60 may be dropped downwardly within upstanding guides 10, below which guides the bricks come to rest upon spaced rest bars 11, the latter paralleling the longitudinal side bars 12 of the main frame, between the ends 65 13 thereof and nearer to one end than the other. The rest bars 11 are in a horizontal plane slightly below the frame side bars and the guide bars 10 terminate at their lower ends in line with the upper edges of the said 70 side bars so that the bricks drop from the guide bars and rest freely on the rest bars for a purpose which will presently appear.

The laterally spaced rest bars 11 are disposed immediately in the rear of the die 75 block 14, upon a transverse beam 15 forwardly of the plunger 16, and between the latter and the die block 14.

The plunger 16 has tapered sides 17 slidably disposed within the inner V-shaped 80 grooves or side bearings 18 bolted in opposing relation to the side bars 12 of the frame, and beyond its forward end, plunger 16 has a rigid brick engaging member 19, spaced therefrom by spacing members 20 85 and preferably of smaller size than that of the bricks to be engaged upon forward movement of the plunger and forced forwardly from the rest bars 11 through the opening 14^a of the die block 14.

To the rear end of the plunger 16, the forward end of a connecting rod 21 is engaged, the rear end of this connecting rod being disposed upon a crank pin 22, connecting 90 spaced gears 23, the latter engaged by the 95 spaced apart gears 24 of a driven shaft 25 in the rear portion of the frame, shaft 25 and the shafts of the gears 23 having bearings respectively indicated at 26 and 27 upon the side rails or bars 12 of the frame. The driven shaft 25 which projects laterally beyond the frame at one end, has upon its projecting end a pulley 28 by means of which it may be belt connected to any suitable source of power of either a stationary 100 or portable nature.

The die block 14 is securely bolted to and braced in connection with the side rails of bars 12 of the frame, and has along the upper and lower edges as well as the sides 110 of its opening 14^a a series of cutter bars of which the annularly disposed bars 29 and

30 along one side and one end of the opening 14^a are securely bolted to the die block by bolts 31. The cutter bars 32 and 33 along the other side and other end of the die block 5 opening are adjustable inwardly and outwardly with their side edges movable in guide brackets 34 securely bolted to the die block, each of these latter cutter bars 32 and 33 being securely fastened to lugs 35 10 projecting into vertical grooves 36 of the die block as best seen in Figure 8 and controlled by springs 37 in said grooves, whose tension is such as to force the cutter bars inwardly with respect to the die block opening 15 under considerable pressure.

Each of the cutter bars has along its inner edge an angularly projecting portion 38 extending away from the die block and serving as a support for the cutter or knife 39 20 secured thereto, and each cutter bar has spaced pairs of ears or clamping brackets 40 secured to and projecting therefrom, between which are bolted, riveted or otherwise fastened as at 41, a cutter guide 42 in the 25 nature of an angular projecting blade whose outer free end has a sharpened edge 43 in the same plane with the inner flat surface of the respective cleaning blade 39.

Thus the bricks fed downwardly within 30 the guides 10 and dropping from the latter onto the rest bars 11, are intermittently engaged by the plunger and forced by the latter through the die block, such brick coming first into engagement with the cutter 35 guides 42 so that the latter, engaging the faces of the brick to be cleaned, adjusts the several cleaning blades 39, so that the latter will be in the planes of the brick faces. This operation takes place by virtue of the 40 yielding qualities of adjustability of the cutter bars 32 and 33 against the tension of their controlling springs 37, and it is obvious that by virtue of the sharpened brick engaging free ends of the cutter guides 45 42, tar or other accumulation upon the surfaces of the brick to be cleaned will be cut through until the free ends or sharpened edges of the cutter guides actually engage the surfaces of the brick. This insures the 50 disposition of the cleaning blades 39 in precisely the desired positions so as to cut along

the surfaces of the brick as the latter pass between the several cutters and on through the opening 14^a of the die block during continued forward movement of the plunger. 55 It is of course contemplated that the stationary cutter bars 29 and 30 may be adjusted with respect to the yieldable cutter bars in adjusting the die to bricks of different sizes, or for this purpose a different die 60 block or grader of less size with properly adjusted cutter bars may be substituted.

It is also contemplated that the cleaning blades 39, which are secured flatwise against the angularly outstanding portions of the 65 cutter bars, may be readily removed for sharpening, although since these blades are so effectively guided as they are in use by the edged cutter guides 42, the necessity for sharpening the cleaning blades is rare particularly if they are formed of a good quality of hardened steel.

My invention as a whole is effective and efficient in use, readily lends itself to speedy 70 operation and thus to an output of cleaned brick in considerable quantity, and is capable of entirely continuous and efficient action throughout long periods with little if any attention except to properly feed the bricks thereto.

I claim:

A machine of the character described, including a die block having an opening therethrough, a series of cutter bars on one face of the die block along the sides and ends of its opening, certain of which cutter bars are stationary and the others of which are adjustable, each of said cutter bars having an angular inner portion projecting away from the die block, a cleaning blade secured to said angular portion, brackets secured to each of the cutter bars, and cutter guides carried by said brackets, each guide being in the form of a blade disposed at right angles to the cleaning blade and projecting slantingly beyond the cutting edge of the cleaning blade and terminating at its free end in a cutting edge disposed in the plane of the cutting edge of the cleaning blade as described.

THEODORE LEONARD KRUPITZER.
